UNITED STATES PATENT OFFICE

EDWARD B. BEDFORD AND MARY G. PARKER, OF ONEIDA, NEW YORK, ASSIGNORS TO ONEIDA COMMUNITY, LIMITED, OF ONEIDA, NEW YORK, A CORPORATION OF NEW YORK

DESIGN FOR A DISH OR SIMILAR ARTICLE

Application filed March 17, 1933. Serial No. 47,501. Term of patent 7 years.

To all whom it may concern:

Be it known that we, EDWARD B. BEDFORD and MARY G. PARKER, citizens of the United States, residing at Oneida, county of Madison, State of New York, have invented a new, original, and ornamental Design for a Dish or Similar Article, of which the following is a specification, reference being had to the accompanying drawing, forming a part thereof, said drawing being a plan view of a dish showing our new design, the essential feature of which is the floral ornamentation on the face of the dish or similar article.

We claim:

The ornamental design for a dish or similar article as shown and described.

In testimony whereof we have hereunto set our hands.

EDWARD B. BEDFORD.
MARY G. PARKER.
